UNITED STATES PATENT OFFICE.

WILLIAM B. HAMM, OF PHILADELPHIA, PENNSYLVANIA.

DESIGN FOR A BADGE.

Specification forming part of Design No. **6,196**, dated October 8, 1872.

To all whom it may concern:

Be it known that I, WILLIAM B. HAMM, of the city of Philadelphia and State of Pennsylvania, have invented a Design for a Society-Badge, of which the following is a specification:

The nature of my design is fully represented in the accompanying drawing, and is described as follows: A short flag-staff, A, sustains a waving flag, B, nearly distended fully, its perpendicular bearing a ratio to its horizontal diameter of 10 to 11. In its central field is displayed a globe, C, reaching nearly to the margin of the field, with the letters "I. O. of G. T." upon the equator, with the words "Faith, Hope, Charity" upon the upper circumference, and with the words "Total Ab-

stinence, Prohibition," on the lower circumference, as shown in the drawing. It may be composed of metal, gutta-percha, textile fabrics, or any other material. I prefer to make the field white and the border D red, where the substance employed conveniently admits of it, but do not consider the colors to be an essential element element of my design; and

What I do claim as my invention, is—

A design for a society-badge composed, lettered, and ornamented substantially in the manner above described.

WILLIAM B. HAMM.
